UNITED STATES PATENT OFFICE.

CARL G. SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

FIREARM.

Original application filed May 17, 1919, Serial No. 297,829. Divided and this application filed December 28, 1921. Serial No. 525,352.

To all whom it may concern:

Be it known that I, CARL GUSTAF SWEBILIUS, a citizen of the United States, residing at New Haven, in the county of New Haven and State of Connecticut, have invented certain new and useful Improvements in Firearms, of which the following is a full, clear, concise, and exact description.

This invention relates to firearms and pertains more especially to repeating or magazine rifles of the take-down type. In one type of take-down rifles, the barrel is engaged with the receiver by a rotary movement of the barrel relative to the receiver. A reciprocating member is carried by the barrel and is adapted, when the barrel is in proper position, to seat in a recess in the front wall of the receiver and prevent the turning of the barrel. This locking member is maintained in locking position by a detent. The action slide is also carried by the barrel and is movable relative to the locking member. The connection between the action slide and the breech mechanism is such that when the breech mechanism is in its locked up position, a forward movement of the action slide will disconnect it from the breech mechanism. Such forward movement of the action slide is normally prevented by another detent. An object of this invention is a single detent which will both maintain the locking member in its locking position and also limit the forward movement of the action slide to prevent its disengagement from the breech mechanism except when the locking member is released.

This type of gun is provided with a box magazine the bottom of which is pivoted and has mounted thereon a spring pressed cartridge feeder lever arm. A further object of this invention is the mounting of the cartridge feeder lever arm on the magazine bottom whereby when the magazine bottom is open the spring pressure on the cartridge feeder lever arm is relieved and the lever arm rests against the inner face of the magazine bottom until the bottom is closed. The cartridge feeder is, therefore, so located that cartridges may be easily inserted in or removed from the magazine.

Other objects and novel features of the invention will be apparent from the following

specification and drawings wherein Fig. 1 is a vertical section through the receiver with the breech open, the breech bolt etc. being in elevation; Fig. 2 is an elevation, partly in section, of the front part of the receiver and barrel, and Fig. 3 is an elevation, partly in section, of the receiver with the magazine bottom open.

A receiver 1 in which is slidably mounted a breech bolt 1^a, carries the barrel 2, which screws into the forward end of the receiver, as indicated at 3, the screw threads being appropriate to permit the ready screwing of the barrel 2 into place and the unscrewing of the same for the purpose of "taking down" the gun. A bracket 4 is carried by the barrel near its rear end and is provided with an aperture through which the preferably tubular member 5 extends into a socket 6 in the front wall of the receiver. In the forward end of the member 5 is cut an elongated slot 7 through which projects a stud 8 rigidly attached to the barrel 2. By means of a screw 9 there is connected to the stud a generally-cylindrical block 10 of suitable dimensions to firmly support the tubular member 5. An aperture 11 is provided in the tubular member through which the screw 9 may be inserted or removed.

A dog or detent 12 is pivotally mounted in a groove 13 cut in the cylindrical block 10 and its end 14 extends beyond the end of the member 5. On the inner end of the detent 12 is a projection 15, the face of which is oblique. In the member 5 are cut two apertures 16 and 17, the former of which is of a size to permit the projection 15 on the detent 12 to completely protrude therethrough under proper conditions and the latter of which is sufficiently small to allow the protrusion of merely the point of the projection. The spring 18 maintains the detent in operative position.

Slidably mounted on the tubular member 5 is a grip or pump handle 19 from which the sliding action rod 20 extends rearwardly into the receiver through a suitable slot in the front wall thereof. The connection between the action rod 20 and the breech bolt 1^a is such that when the breech bolt is in locked position, the action rod may be disengaged therefrom merely by a forward

movement thereof. This connection is fully disclosed in my copending application Serial No. 297,829, filed May 17, 1919. This forward movement is normally prevented by the engagement of the forward end of the grip 19 with the projection 15 when the latter protrudes through the aperture 16, as shown in Fig. 1.

To take down the gun, the end of the member 5 is grasped with the thumb and middle finger and the detent 12 operated with the fore finger in such a way as to withdraw the projection 15 thereof through the aperture 16. The tubular member is then moved outwardly and the detent released. The outward movement of the tubular member is checked by the contact of the forward edge of the projection 15 with the side of the aperture 17. This movement disengages the inner end of the member 5 from the socket 6. The action rod 20 is then moved forward by means of the grip 19 until it is clear of the receiver, this being possible because of the aforementioned detachable connection between the breech bolt and the action rod and the fact that the projection 15 no longer extends in front of the grip. The barrel is then unscrewed from the receiver. In putting together the gun, the detent 12 and the tubular member 5 are arranged with the projection 15 in the aperture 17 and the handle 19 forward. The barrel is then screwed into the receiver. A pull on the grip slides the action rod into the receiver and into operative engagement with the breech bolt, and a pull on the tubular member seats it in the socket 6, the detent being cammed up by the engagement of the oblique face of the projection 15 with the rear edge of the aperture 16.

The detent 12 serves to hold the tube 5 in its locking position and also serves to limit the forward movement of the action rod when the gun is assembled. This single detent performs the functions which have heretofore required two or more detents. The structure is therefore simplified and the taking down of the gun made easier and quicker,

In the bottom plate 21 of the receiver 1 is cut an aperture through which extends the box like magazine 22 which is closed by the pivoted lid 23. Pivotedly mounted on the lid 23 is a lever 24, the shorter arm of which is engaged by the free end of the leaf spring 25 to urge said lever into the position shown in Fig. 3. A plate or cartridge feeder 26 is pivoted to the end of the longer arm, and a spring 27 cooperates with the forward end of said feeder to tend to move said feeder into alinement with said lever as shown in Fig. 3. Just in advance of the trigger guard is a spring pressed plunger 28 which engages, when the lid is shut, the short arm of the lever 24. As this spring is considerably

stronger than the leaf spring 25, it forces the longer arm of the lever 24 upwardly and furnishes the force to elevate the cartridges into position to be chambered. The downward movement of the plunger 28 is limited by the stop 29 which is so arranged that when the lid is open the plunger does not engage the short arm of the lever 24. The lever 24 is, therefore, free to assume the position shown in Fig. 3 under the influence of the spring 25. The rear part of the upper end of one wall of the magazine is bent in as at 30 to form a stop to position a cartridge in the path of the member 31 on the breech bolt 1^a and is slanted upwardly toward the front wall of the receiver to cause a cartridge to be tilted by the feeder 26 and it also acts as a guide to direct the cartridge into the barrel 2. A resilient detent 32 cooperates with a hook 33 on the lid 23 to hold the latter in its closed position. By virtue of this arrangement, when the lid is open the lever 24 is held against the lid 23 thereby allowing the easy insertion of cartridges into the magazine. As the lid is closed, the short arm of the lever 24 is engaged by the plunger 28 and the lever is swung into engagement with cartridges in the magazine to force them upwardly and feed them successively against the bend in position 30.

It is, of course, understood that variations in the structure of this gun may be made without in any way departing from the spirit of the invention as set forth in the appended claims.

This application is a division of my copending application Serial No. 297,829, filed May 17, 1919.

What is claimed is:

1. In a take-down repeating firearm, a receiver, a barrel, means for engaging the barrel with the receiver by a rotary movement of one part relatively to the other, a member carried by the barrel and movable into and out of engagement with the receiver to prevent the rotation of the barrel relative thereto when the parts are assembled, a reciprocating action rod carried by said member and arranged to enter said receiver, and a detent both to engage said member to lock it in engaging position with said receiver and to engage the action rod to prevent its withdrawal from the receiver.

2. In a take-down repeating firearm, a receiver, a barrel, means for engaging the barrel with the receiver by a rotary movement of one part relatively to the other, a member carried by the barrel and movable into and out of engagement with the receiver to prevent the rotation of the barrel relative thereto when the parts are assembled, a reciprocating action rod carried by said member and arranged to enter said receiver, and a detent carried by said barrel both to engage said member to lock it in engaging

position with said receiver and to engage the action rod to prevent its withdrawal from the receiver.

3. In a take-down repeating firearm, a receiver, a barrel, means for engaging the barrel with the receiver by a rotary movement of one part relatively to the other, a member carried by the barrel and movable into and out of engagement with the receiver to prevent the rotation of the barrel relative thereto when the parts are assembled, a reciprocating action rod carried by said member and arranged to enter said receiver, a recess in one end of said member, and a 10 detent carried by said barrel extending into said recess both to engage said member to lock it in engaging position with said receiver and to engage the action rod to prevent its withdrawal from the receiver.
- 20 4. In a take-down repeating firearm, a receiver, a barrel, means for engaging the barrel with the receiver by a rotary movement of one part relatively to the other, a member carried by the barrel and movable into and out of engagement with the receiver to prevent the rotation of the barrel relative thereto when the parts are assembled, a reciprocating action rod carried by said member and arranged to enter said receiver, a recess in one end of said member, a support carried by said barrel extending into said recess, locking means carried by said support, and an aperture in the wall of said recess through which the locking means projects to maintain said member in engaging position with the receiver and to engage said action rod to prevent the withdrawal thereof from the receiver.

- 40 5. In a take-down repeating firearm, a receiver, a barrel, means for engaging the barrel with the receiver by a rotary movement of one part relatively to the other, a member carried by the barrel and movable into and out of engagement with the receiver to prevent the rotation of the barrel relative thereto when the parts are assembled, a reciprocating action rod carried by said member and arranged to enter said receiver, a recess in one end of said member, a support 45 carried by said barrel and extending into said recess, a lever pivoted to said support, and aperture in the wall of said recess, a lug on said lever adapted to project through said aperture and engage the end of the action rod.

- 55 6. In a take down repeating firearm, a receiver, a barrel, means for engaging the barrel with the receiver by a rotary movement of one part relatively to the other, a member carried by the barrel and movable into and out of engagement with the receiver to prevent rotation of the barrel when the

parts are assembled, a reciprocating action rod arranged to enter said receiver, and a pivoted detent both to engage said member to lock it in engaging position with said receiver and to engage the action rod to prevent its withdrawal from the receiver. 65

7. In a take down repeating firearm, a receiver, a barrel, means for engaging the barrel with the receiver by a rotary movement of one part relatively to the other, a member carried by the barrel and movable into and out of engagement with the receiver to prevent rotation of the barrel when the parts are assembled, a reciprocating action rod arranged to enter said receiver, and a lever pivotally supported from said barrel both to engage said member to lock it in engaging position with said receiver and to engage the action rod to prevent its withdrawal from the receiver. 70

8. In a take down repeating firearm, a barrel, means for engaging the barrel with the receiver by a relative rotary movement, 85 a tubular member slidably carried by the barrel and movable into locking engagement with said receiver, a sliding action rod extending into said receiver, and a detent within said tubular member both to engage said member to lock it in engaging position with said receiver and to engage the action rod to prevent its withdrawal from the receiver.

9. In a take down repeating firearm, a barrel, means for engaging the barrel with the receiver by a relative rotary movement, a tubular member slidably carried by the barrel and movable into locking engagement with said receiver, a sliding action rod extending into said receiver, and a lever 90 pivotally mounted within said tubular member both to engage said member to lock it in engaging position with said receiver and to engage the action rod to prevent its withdrawal from the receiver. 95

10. In a take down repeating firearm, a barrel, means for engaging the barrel with the receiver by a relative rotary movement, a tubular member slidably carried by the barrel and movable into locking engagement with said receiver, a sliding action rod extending into said receiver, a cylindrical member carried by said barrel and located within said tubular member, and a lever pivoted to said cylindrical member, said 100 lever being adapted to project through an aperture in said tubular member to maintain it in engaging position with said receiver and to engage the end of said action rod to prevent its withdrawal from the receiver. 105

In witness whereof I hereunto attach my signature this 19th day of December 1921.

CARL G. SWEBILIUS.
